UNITED STATES PATENT OFFICE

149,601

DESIGN FOR A VEHICLE HOOD ORNAMENT OR SIMILAR ARTICLE

Howard F. Yaeger, Detroit, Mich., assignor to Packard Motor Car Company, Detroit, Mich., a corporation of Michigan

Application October 18, 1946, Serial No. 134,024

Term of patent 14 years

(Cl. D14—18)

To all whom it may concern:

Be it known that I, Howard F. Yaeger, a citizen of the United States, residing at Detroit, county of Wayne, State of Michigan, have invented a new, original, and ornamental Design for a Vehicle Hood Ornament or Similar Article, of which the following is a specification, reference being had to the accompanying drawing, forming a part thereof.

Figures 3 and 4 are respectively top plan and side elevational views of my new vehicle hood ornament; and

The characteristic features of my design reside in the portions shown by means of full lines in the drawing.

I claim:

The ornamental design of a vehicle hood ornament or similar article, substantially as shown and described.

HOWARD F. YAEGER.
